US00D788727S

(12) **United States Design Patent** (10) **Patent No.:** **US D788,727 S**
(45) **Date of Patent:** **** Jun. 6, 2017**

(54) **PORTABLE ELECTRONIC DEVICE**(71) Applicant: **HTC Corporation**, Taoyuan, Taoyuan County (TW)(72) Inventors: **Yien-Chun Kuo**, Taoyuan (TW); **Hung-Yi Huang**, Taoyuan (TW); **Feng-Chen Chang**, Taoyuan (TW); **Shih-Hsun Ou**, Taoyuan (TW); **Chih-Ling Chien**, Taoyuan (TW)(73) Assignee: **HTC Corporation**, Taoyuan (TW)(**) Term: **14 Years**(21) Appl. No.: **29/510,201**(22) Filed: **Nov. 25, 2014****Related U.S. Application Data**

(62) Division of application No. 29/443,348, filed on Jan. 16, 2013.

(51) **LOC (10) Cl.** **14-03**(52) **U.S. Cl.**USPC ..... **D14/138 G**(58) **Field of Classification Search**

USPC ..... D14/138 G, 138 AD, 341, 346, 138 R, D14/496, 203.1, 203.4, 203.5, 203.6, D14/203.7, 248, 218; D21/517, 329, 331; D10/65, 78; 455/575.1, 575.3, 575.4, 455/556.2; 361/679.3, 679.56; 379/433.01, 433.04; D13/168

Primary Examiner — Jeffrey D Asch*(74) Attorney, Agent, or Firm* — Birch, Stewart, Kolasch & Birch, LLP**CLAIM**

The ornamental design for portable electronic device, as shown and described.

DESCRIPTION

FIG. 1 is a front perspective view of a portable electronic device in accordance with our new design;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a rear perspective view thereof; and,

FIG. 10 is another rear perspective view thereof.

1 Claim, 9 Drawing Sheets(56)
